UNITED STATES PATENT OFFICE

2,349,887

HOSE CLAMP WRENCH

Clarence M. Selberg, Los Angeles, Calif.

Application May 14, 1943, Serial No. 487,017

1 Claim. (Cl. 81—119)

This invention relates to new and useful improvements in wrenches and like tools, the principal object of the invention being to provide a wrench or key whereby the usual clamping screw of hose clamps and the like can be readily reached at near inaccessible places.

Another important object of the invention is to provide a wrench or operating key for wing headed screws whereby said screws can be actuated in crowded or near inaccessible places, with but a small effort on the part of the workmen.

Other objects and advantages of the invention will become apparent to the reader of the following description.

In the drawings:

Figure 1 represents a fragmentary side elevational view showing the wrench being used in one position.

Figure 2 is a section taken on the line 2—2 of Figure 1.

Figure 3 is a fragmentary side elevational view showing the wrench being used in a different position.

Figure 4 is a fragmentary side elevational view showing the wrench being used in a third position.

Figure 5 is a top plan view of the wrench.

Figure 6 is a longitudinal sectional view taken substantially on the line 6—6 of Figure 5.

Figure 7 is an end elevational view of the wrench.

Referring to the drawings wherein like numerals designate like parts, it can be seen that this device is especially adapted for use in conjunction with tube and hose connections on aircraft, automobiles, trucks, and other commercial and military mobile units. Numeral 5 denotes a pipe or tube, while numeral 6 denotes a hose end which is to be clamped to the pipe 5. A clamp generally referred to by numeral 7 and of conventional design consists of a band 8, a pressure body or block 9 and a screw 10, this screw being of the type having a wing or flat head 11.

The present invention, which is a wrench for

actuating the screw 10 is generally referred to by numeral 12 and consists of a T-shaped structure as is clearly represented in Figure 1. This T-shaped structure consists of a leg 13 having a crossed head 14. A channel 15 extends longitudinally of the leg 13 and merges with a channel 16 extending from end to end of the head 14. The lower end of the shank 13, that is, the free end is bifurcated as at 17, so as to form furcations 18 capable of straddling the head 11 of a screw 10 when the wrench is to be used in the position shown in Figure 2.

The channel 15 is to be used when the wrench has to assume the position shown in Figure 3, while the cross channel 16 comes into play when the wrench must be used in the position shown in Figure 4.

Obviously, the wrench can be stamped from a single sheet of metal or otherwise constructed, 20 to arrive at the T-formation and the channels and bifurcation above specified.

While the foregoing specification sets forth the invention in specific terms, it is to be understood that numerous changes in the shape, size and 25 materials may be resorted to without departing from the spirit and scope of the invention as claimed hereinafter.

Having described the invention, what is claimed as new is:

30 A wrench of the character described comprising a shank straight throughout its length and a cross head at one end of said shank projecting from opposite sides thereof and straight throughout its length, the cross head being U-shaped in cross section to provide a straight and unobstructed channel extending the full length of the cross head and having inner and outer side walls, the shank being also U-shaped in cross section to provide a straight and unobstructed channel 35 having side walls and communicating with the channel of the cross head through the inner side wall thereof, and said shank being slotted from its outer end along the bottom of its channel to form flat jaws of free end portions of its walls.

CLARENCE M. SELBERG.
